UNITED STATES PATENT OFFICE.

FRANCIS M. OSTEEN, OF GREENVILLE, SOUTH CAROLINA.

ATTACHMENT FOR PICKERS OR LAPERS.

1,184,203.

Specification of Letters Patent.

Patented May 23, 1916.

Application filed March 10, 1915. Serial No. 13,378.

To all whom it may concern:

Be it known that I, FRANCIS M. OSTEEN, a citizen of the United States, residing at Greenville, in the county of Greenville and 5 State of South Carolina, have invented certain new and useful Improvements in Attachments for Pickers or Lappers, of which the following is a specification.

My invention appertains to improvements 10 in attachments for that class of machines used in textile manufacturers, which are designated as pickers or as lapping machines, and in such machines the raw fiber is delivered to the picker, usually by means of an 15 air blast delivered through a pipe of relatively small area the fiber then being collected and distributed by means of a condenser. The fiber is removed from the condenser by a stripping apparatus and is deposited 20 upon a traveling apron which in turn feeds the fiber to the beater. With such a system there is a lack of uniformity in the delivery of the fiber to the traveling apron, which results in the presence of thin spots 25 or strips in the lap which is made on this machine, such thin spots or strips resulting in the lap splitting and tearing in the subsequent steps through which it is passed.

The object of my invention is to provide 30 means located in the flue or feed chamber below the condenser and its clearer roll and above the apron, such means consisting of an oscillatory member that is moved in a horizontal plane at right angles to the path 35 of the fiber, the range of movement of the oscillatory or vibratory member or rod being such as to cover the full width of the flue or feed chamber, such means in operation insuring an even distribution of the fiber over 40 the apron which will result in the production of a lap in which there is an absence of thin spots or strips.

In the accompanying drawings which 45 illustrate a preferred form of my invention, Figure 1 is a side elevation of an accepted form of picker or lapper showing my improvement applied thereto. Fig. 2 is a plan view. Fig. 3 is an end elevation viewed from the direction of the arrow A, on Fig. 1, 50 and Fig. 4 is a detail view.

The picking or lapping machine receives its supply of fiber through the pipe 1, which discharges into a chamber that contains a revolving condenser 2 from which the fiber 55 is removed by a clearer roll 3, the fiber taking from the condenser falling or being de-

posited upon a traveling apron 4 which delivers the same to feed rolls 5. The feed rolls 5 delivers the fiber to a beater located within a casing 6, from whence it is carried 60 to a second condenser that is within the casing 7 and from thence to calender rolls 8 leaving the same in a continuous sheet of supposedly even thickness and of the full width of the belt 4 and the condensers. 65 After leaving the calender rolls 8, the bat passes to the rolls 9 and is wound upon a mandrel 10 to form the roll or lap. In a device of the character above described in operation any failure to start the fiber 70 through the feed rolls 5 the full width of the feed rolls and in a mass of even thickness results in uneven or thin places in the finished lap; for instance, should the fiber be deposited more on one side of the apron 4 75 than on the other side the resulting sheet of fiber which forms the lap will be thin on one side and when the lap is later unwound in the further process of manufacture this thin place in the lap will break, causing what is 80 technically known as a split lap.

My invention is designed to eliminate uneven places in the lap and to provide for an even deposit of the fiber upon the apron, and with such end in view the shaft of the 85 condenser 2 is provided with a pulley 12, that is engaged by a belt or band 13 which also engages a pulley 14 to drive a shaft maintained by a bracket 15 which is attached to the trunk or casing in the upper part of 90 which the condenser 2 is mounted, and in the lower part the apron 4. The lower end of the shaft that is carried by the bracket 15 has attached thereto a crank disk 16, having therethrough a slot 16^a through which is 95 passed a bolt for connecting a link 17 with a rocker arm 18. The rocker arm 18 has a depending stud 18^a that is seated in a bearing block 19 which is clamped upon a rod 19^a that is suitably clamped to the trunk by 100 eyebolts and a rod on the opposite side of the trunk from the rod 19^a, which supporting means locates the bearing block 19 centrally with respect to the trunk, as shown in Fig. 3. The rocker arm 18 is provided with 105 apertured lugs and set screws for appropriately associating therewith a rod 20 which extends through an opening 21 through the trunk to position the rod below the condenser 2 and its clearer roll 3. The rod 20 110 may be bent as shown in Fig. 1 so as not to engage the condenser 2 and the clearer roll

3 below which it oscillates or vibrates so as to intercept the fiber as it leaves the condenser 2 and its clearer 3, preventing the fiber being deposited upon the apron in a mass at any one point and insuring an even distribution of the fiber over the entire width of the apron, so as to insure uniformity in the resultant lap.

The oscillatory member or rod 20 may be 10 adjusted upon the rocker arm 18 and by varying the point of attachment of the link 17 with the crank or disk 16 the distance which the member or rod 20 moves may be varied to change the amplitude of the oscillations, the oscillations being preferably in a horizontal plane which is at right angles to the path of the fiber on its way to the picker, and in practice it is desirable that the rod 20 and parts associated therewith shall be adjusted so that the vibratory or oscillatory member shall have a range of movement equal to the full width of the feed chamber or trunk. The rod or member 20 is preferably bent so that its major portion which is located in the trunk will be below the condenser and its clearer roll, and by locating the downward extending portion of the rod below the clearer roll such bent rod not only clears the condenser but being inclined 25 downward the rod will not retain the cotton which falls thereon.

The invention hereinbefore described may be varied by duplicating the oscillatory rod or bar at different places in the trunk to engage the fiber as it goes from the condenser 2 and its clearer roll 3 to the feed apron of the picker, and the invention is not only applicable to pickers or lappers but may be applied to several types or forms of carding 35 machines that form bats or laps.

I claim:

1. In combination with a fiber picking ma-

chine, an oscillatory rod having a downwardly inclined portion, said rod being mounted in a trunk or way below the clearer 45 roll for a condenser to intercept the path of the fiber on its way to the lap or bat forming mechanism of the picking machine.

2. In a machine for forming laps or bats, a trunk or way for fiber, a condenser and 50 clearer roll for feeding fiber to the trunk or way, an apron or carrier upon which the fiber is deposited, and an oscillatory rod or member the major portion of which is inclined to extend downward, said rod or member being mounted to move and to traverse the path of the fiber before being deposited upon the apron or carrier.

3. The combination in a fiber picking or lapping machine, of a trunk or way, a bent 60 rod maintained by the trunk or way and located centrally within the trunk or way the rod being of a length sufficient to reach from one to the other side of the trunk or way to engage the fiber on its way through the 65 trunk or way, and means for oscillating the rod in a substantially horizontal plane from one of the rotary parts of the picker or lapper.

4. The combination in a fiber picking machine having a condenser, means for removing fiber from the condenser, a trunk or way for the fiber removed from the condenser, and an apron located at the lower portion of the trunk, of a bar having an inclined portion, said bar being mounted upon a rocker arm, a crank associated with the rocker arm, means for supporting the rocker arm and means for rotating the crank associated with the drive shaft of the condenser.

FRANCIS M. OSTEEN.
